UNITED STATES PATENT OFFICE.

JOSEPH W. TATUM, OF PHILADELPHIA, PENNSYLVANIA.

STAND FOR CALENDARS.

No. 901,754.

Specification of Letters Patent.

Patented Oct. 20, 1908.

Application filed February 24, 1908. Serial No. 417,331.

To all whom it may concern:

Be it known that I, JOSEPH W. TATUM, a citizen of the United States, residing in the city and county of Philadelphia, State of Pennsylvania, have invented a new and useful Stand for Calendars, of which the following is a specification.

My invention relates to a new and useful stand for calendars and consists in forming 10 the same of a single piece or blank.

It further consists of novel means for locking the parts in operative position.

It further consists of novel details of construction, all as will be hereinafter fully set 15 forth.

Figure 1 represents a view of the blank employed in forming my stand for calendars. Fig. 2 represents a perspective view of the stand in operative position. Fig. 3 20 represents a sectional view on line $x-x$, Fig. 2, with the calendar shown in dotted lines. Fig. 4 represents a sectional view on line $y-y$ Fig. 1.

In constructions now in use upon the 25 market, owing to the size of the same it has been found impracticable to send same by mail. My invention is designed to overcome this objection and while I have shown a form which in practice gives satisfactory 30 and reliable results, it will be understood that the arrangement of the parts may be varied and other instrumentalities may be employed which will serve the same purpose and I do not therefore desire to be limited 35 in every instance to the exact construction herein shown and described but desire to make such changes as may be necessary.

Similar numerals of reference indicate 40 corresponding parts in the figures. Referring to the drawings. 1 designates a blank from which the stand for calendars is formed, said blank having the creases or 45 scoring 2 and 3 therein and having the beads 4, 5 and 6 formed at suitable points, in order 50 to stiffen and strengthen the base of the stand.

8 designates the support which is provided 55 with the beads 9, said support being adapted to be bent downwardly from the back 10 from which it is cut in order to properly 60 support the base 11 of the stand. Cut from the base 11 are the strips or arms 12 and 13, which are curved in cross-section, as will best be understood from Figs. 3 and 4. Suitable 65 holes or openings 14 are provided in the top back 10 at the proper points therein.

In order to properly bend said arms 12 and 13, I provide the creases or scoring 15 and 16 in each of said arms. The operation of placing the parts in proper position will be 70 readily seen.

The back 10 is bent up at the crease 2, in order to assume the position with respect to the base 11, as seen in Figs. 2 and 3. The support is bent downwardly at the proper 75 angle, so that said base 11 is held at an angle. The arms 12 and 13 are then bent upwardly and are bent at the scoring 15 and passed through the openings 14 after which the ends 17 of said arms are bent to engage with 80 the rear of the back 10, it being understood of course that before the parts are placed in this position the calendar or note sheets 18 are placed upon these arms 12 and 13 and will be held in position, as seen in Fig. 3. 75 The foot piece 19 is now bent up along the creases 3 and thus will be located in position. Each sheet of the calendar 18 can be moved over on the arms 12 and 13 and supported against the back 10, as best understood from 85 Fig. 3, the position which the sheets assume being indicated by the reference numeral 20.

From the above it will be understood that I have provided a device which is strong and durable, is simple in operation, can be mailed 85 flat and can be quickly and easily set up for use. In addition, the foot piece 19 will serve as a pencil support, the pencil being shown in dotted lines at 21, in Fig. 3.

I desire to call attention to the fact that 90 the stand, as above described, serves as a filing stand for the memoranda made daily or, in other words, the calendar slips are not removed from the stand but can be retained 95 thereon without interfering with the remaining slips which are still to be used. This is accomplished by reason of the arrangement of the arms 12 and 13 and the back 10, the position of the slips, which are retained as already stated, being shown in dotted lines 100 at 20. The upright portion of the arms 12 and 13, as will be noted, extends at a suitable angle with respect to the base 11, in order that the sheets 18 of the calendar are held in proper position and when the said 105 sheets are moved over to rest against the back 10, it will be noted that a portion of the arms 12 and 13 extends substantially horizontal or at a suitable angle with respect to the back 10, in order to properly support the 110 sheets in the position as shown at 20.

Having thus described my invention, what

I claim as new and desire to secure by Letters Patent, is:—

1. In a device of the character described, a base, a back formed at an angle to the base and side arms integral with said base adapted to be connected with said back.
2. In a device of the character described, a base, arms integral with said base, a back formed at an angle to said base, means for connecting said arms with said back and a support integral with said back.
3. In a device of the character described, a base, a support therefor, a back situated at an angle with respect to said base, arms integral with said base and bent to engage with said back.
4. In a device of the character described, a base, a back situated at an angle with respect

to said base, a support bent upon said back, arms bent upwardly from said base and passing through openings in said back, the ends of said arms being bent to engage with said back and a foot piece on said base.

5. In a device of the character described, a base, a back projecting at an angle from said base and integral therewith, a support bent on said back and integral therewith; arms projecting upwardly from said base and integral therewith, said arms being curved in cross section and having a portion thereof passing through openings in said back and a foot piece integral with said base.

JOSEPH W. TATUM.
